UNITED STATES PATENT OFFICE.

WALTER H. TIBBALS, OF SYRACUSE, NEW YORK, ASSIGNOR TO SYRACUSE-VALLEY CORPORATION, OF SYRACUSE, NEW YORK, A CORPORATION OF NEW YORK.

AUTOMATIC CLOSURE CONTROL.

Application filed January 25, 1923. Serial No. 614,771.

To all whom it may concern:

Be it known that I, WALTER H. TIBBALS, a citizen of the United States of America, and a resident of Syracuse, in the county 5 of Onondaga, in the State of New York, have invented new and useful Improvements in an Automatic Closure Control, of which the following, taken in connection with the accompanying drawings, is a full, 10 clear, and exact description.

This invention relates to clock-controlled weight supporting and releasing mechanism for holding a self-closing window sash in an open position for a pre-determined interval of time and then automatically releasing it to allow it to close at the end of that period, although it is evident, certain features of the invention may be used for supporting and releasing other devices such 20 as draft and check dampers of house heaters, self-closing valves and the like.

The main object is to combine in a unitary article of manufacture any of the well-known types of alarm clocks preferably of 25 the smaller size with the sash holding means in such manner that when the alarm mechanism is set to release at a certain time, a part of said alarm mechanism usually at the back of the clock will be set in motion 30 to release a sash supporting pawl and thereby allow the sash to close.

One of the specific objects is to assemble the sash supporting pawl and its clock-controlled detent in such relation that the 35 detent may be tripped by a part of the clock mechanism without appreciably affecting the regular operation of the clock and at the same time to bring those parts into close compact relation without sacrificing their durability and efficiency.

Another object is to provide the back of the clock with a supporting plate which is 40 hinged to the supplemental case containing the sash supporting pawl and detent in such 45 manner as to form a cover plate or door for the supplemental case and permit said cover plate with the clock thereon to be opened for re-setting the pawl and detent and also for rewinding the clock and resetting the alarm mechanism when desired.

Other objects and uses relating to specific

parts of the device will be brought out in the following description.

In the drawings:

Figure 1 is an inner face view of a portion 55 of a window frame and lower and upper sash together with one of my improved sash supporting and releasing devices in operative position upon the window casing, the one side shown as holding the lower sash 60 in partially opened position.

Figure 2 is an enlarged face view of the detached device exclusive of the chains or cables.

Figure 3 is a horizontal sectional view 65 taken on line 3—3, Figure 2 except that the clock is shown in top plan.

Figure 4 is a face view of the supplemental case containing the sash supporting pawl and detent with the cover removed, and also 70 showing the adjacent portion of the clock mechanism for tripping the detent.

In order that my invention may be clearly understood, I have shown a portion of a window frame —A— and lower and upper 75 sash —a— and —a'— together with the sash supporting and releasing mechanism operatively connected to the lower sash for holding it in a partially opened position.

This sash supporting and releasing mechanism 80 comprises an ordinary clock —1— preferably of small size having a spindle —2— which constitutes a part of the alarm mechanism of the clock to be set and held against rotation for any period of time 85 within say, twelve hours and to be automatically released by the clock mechanism in the well-known manner for alarm clocks at the end of that period.

The back of the clock may be secured in 90 any well-known manner to a back plate —3— which in this instance forms a cover plate for a supplemental case —4— and is hinged at —5— to one end of said supplemental case to swing through an arc 95 of substantially 90 degrees or from its closed position shown by full lines in Figure 3 to its open position shown by dotted lines in the same figure, the other end of the cover plate —3— being provided 100 with a spring catch —6— adapted to frictionally engage in the recess —7— in the

corresponding end of the supplemental case —4—, said catch also constituting a finger piece whereby the cover plate may be conveniently opened by hand.

5 The spindle —2— extends through an opening in the back plate —3— into the interior of the supplemental case —4— and is provided with one or more crank arms —8— adapted to revolve with the spindle 10 when the latter is released after having been previously set against rotation in the usual manner for alarm clocks, although the alarm is not shown.

15 Secured to one of the upright sides of either sash for example the lower sash —a—, is an upright guide consisting in this instance of a bead chain cable —9— attached at both ends to the sash near the lower and upper edges thereof and having 20 its remaining portions free.

25 A similar sash supporting cable —10— is provided at its lower end with a ring or loop —11— which is slidable lengthwise over and upon the guide chain —9— and is adapted to be locked thereto by tilting it 30 from a horizontal position, as for example, by upward pull upon the chain —10—.

35 The upper end of this chain —10— is also provided with a ring or loop —12— for engagement with one end of a holding pawl or lever —13— which is pivoted intermediate its ends to the inner face of the back wall of the supplemental case —4— by means of a pivotal pin or stud —14— so that 40 its outer end may extend through a slot or opening —15— in the corresponding end of said case extending downwardly and laterally into the adjacent portion of the bottom of the case to permit the holding pawl or lever —13— to swing from a substantially horizontal normal position toward a vertical position, the end wall of the slot in the corresponding end of the case constituting a stop shoulder —16— for limiting the upwardly swinging movement of the outer end 45 of the lever while the opposite end wall of the slot in the bottom of the case forms a stop shoulder —17— to limit the release movement of the lever to less than an angle of 50 degrees whereby its inner end may cause the lever to return to its horizontal position.

55 A detent lever —18— preferably made in the form of a bell crank is pivoted at its angle to the back wall of a case —4— by means of a pivotal pin or stud —19— directly over the inner end of the pawl —13— when the latter is in its normal position so that one of its arms as —20— will automatically swing by its own weight into engagement with the upper edge of the inner end of the pawl —13— until limited by a stop pin —22— projecting inwardly from the back of the case —4—.

60 65 The other arm —21— of the bell crank

lever —18— extends horizontally from the pivotal pin —19— toward and into the path of movement of the crank arm —8— of the clock spindle —2— and is preferably made of relatively thin spring metal capable of yielding laterally in case the crank arm —8— should be more or less crosswise of the adjacent end thereof when closing the cover plate —3— with the clock thereon.

In this event, the inner edge of the crank arm —8— will simply engage the face of the spring and press the same backwardly against its own tension without in any way affecting the position of the detent arm —20— and would remain in this position 75 until the crank arm was released and then allowed to rotate thereby causing it to travel out of engagement with the inner face of the spring which latter would then be returned by its own tension against a stop pin —23— 80 ready to be engaged and tripped by the crank arm —8— during its continued rotation.

85 The entire device may be secured to the window casing adjacent the sash by one or more wood screws —24— and when properly secured in place, the outer end of the holding pawl or lever —13— projects slightly beyond the window sash and is notched at 90 —25— to receive the ring —12— on the upper end of the cable —10— and thereby to hold said cable in operative engagement with the pawl when the latter is held in a substantially horizontal position by the detent —18—.

95 The sash —a— may be raised and lowered but independently of the cable —10— by simply holding the ring —11— between the fingers in a substantially horizontal position and when opened to the desired position for 100 ventilation or other purposes, the ring —11— will be caught in the links of the adjacent portion of the guide —9— while the ring —12— at the upper end of the cable —10— will be engaged with the outer end of the pawl —13—.

105 Now, if the device has been set to hold the window open for ventilation purposes during the night and to release the window to allow it to close at say 7 o'clock in the morning the rotation of the spindle —2— and its crank arm —8— will at that time trip the detent —18— to the position shown by dotted lines in Figure 4 and thereby release the pawl —13— whereupon the weight 115 of the sash drawing down upon the cable —10— will rock the outer end of the pawl —13— downwardly toward a vertical position or until the ring —12— disengages 120 therefrom, whereupon the inner end of the pawl will immediately return it to a horizontal position against the stop —16— or 125 will at least permit it to be reset by hand in holding engagement with the detent —18—.

This latter operation may be readily accomplished and the clock re-wound and its alarm mechanism re-set by simply swinging the cover plate —3— with the clock thereon 5 to its open position which permits access to the detent and pawl in the case —4— and also permits access to the winding and setting mechanism at the back of the clock.

It is evident from the foregoing description 10 that this device may be used for supporting various weighted members for automatically releasing them at the end of said interval of time.

I claim:

15 1. In a weight supporting and releasing mechanism, a case having a hinged cover plate adapted to be opened and closed, a clock mechanism mounted on the cover plate to swing therewith and having one of 20 its members rotatable and adapted to be set against rotation to be released at any predetermined time, said member projecting into the case when the cover plate is closed, a pawl pivotally mounted within the case

25 and having one end projecting through an opening therein, a detent within the case engaging the pawl to hold the latter against movement and a portion thereof extending into the path of movement of said member 30 to be tripped thereby when the member is rotated, in combination with a weighted member, and connections between said detent and weighted member for holding the latter against movement by its own weight.

35 2. In combination with a weighted member adapted to move in one direction by its own weight, a relatively stationary case, a pawl pivoted intermediate its ends within the case and having one end projecting

40 through an opening therein, supporting means for the weighted member normally carried by the outer end of said pawl, a pivoted detent within the case engaging the inner end of the pawl for holding the pawl 45 against movement by the weighted member, and clock-controlled means on the case for tripping the detent at a certain time.

3. In a weight supporting and releasing device, the combination with a weighted 50 member adapted to move in one direction by its own weight, a guide on said member, a supporting member adjustable along said guide and provided with means for holding it in its adjusted position to support the 55 weighted member in different positions, a holding pawl for said supporting member, a detent for the pawl, and clock-controlled means for tripping the detent at a pre-determined time.

60 4. In combination with a weighted member adapted to move in one direction by its own weight, a stationary case having a

hinged cover plate, means for supporting the weighted member including a pawl and a detent therefor, both pivotally mounted 65 within the case independently of the cover plate, and clock-actuated means mounted on the cover plate to swing therewith and provided with means for tripping the pawl at a pre-determined time when the cover plate 70 is closed.

5. In combination with a window sash and a frame therefor, a casing mounted on the window frame, means for holding the window sash against closing including a 75 detent within the case, and clock-controlled means mounted on the case for tripping the detent at a predetermined time to release the sash, said case being provided with a hinged cover plate and the clock and its detent-tripping means being mounted on the cover plate to swing therewith.

80 6. In combination with a self-closing window sash and a frame therefor, an upright guide mounted on one side of the window sash, a holding member having its lower end provided with means adjustable along the guide and interlocked therewith to hold the sash in different positions, a case mounted on the window frame and provided with a hinged cover plate, a pawl pivoted intermediate its ends within the case and extending through an opening therein for supporting the upper end of the sash holding member, a detent pivotally mounted within the 85 case for holding the pawl against movement by the sash, and a clock mounted on the cover plate to swing therewith, and provided with means for engaging and tripping the detent at a pre-determined time when 90 the cover plate is closed.

95 7. A sash holding and releasing means as described in claim 6 in which the portion of the detent engaged by the tripping means of the clock is yielding in the direction of 100 the closing movement of the cover plate to enable the cover plate to be closed in case its yielding part should lie in the path of movement of said tripping means when closing the door.

105 8. A sash supporting device including a detent, and a motor actuated member for tripping the detent movable to and from its operative position, the portion of the detent engaged by said member being yielding in 110 case it lies in the path of movement of said member when the latter is moved to its operative position.

In witness whereof I have hereunto set my hand this 19th day of January, 1923.

WALTER H. TIBBALS.
